(57) **CLAIM**

The ornamental design for a decorative light for vehicle, as shown and described.

DESCRIPTION

FIG. 1 is a perspective view of a decorative light for vehicle showing my new design;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view of the decorative light for vehicle, the broken line showing for illustrative purposes only and forming no part of the claimed design.
